US0D1052947S

(12) **United States Design Patent** (10) **Patent No.:** **US D1,052,947 S**
(45) **Date of Patent:** **** Dec. 3, 2024**

(54) **BEVERAGE MAKER**

(71) **Applicant:** **GUANGDONG MIDEA CONSUMER ELECTRIC MANUFACTURING CO., LTD.**, Foshan (CN)

(72) **Inventors:** **Mengmeng Zhang**, Guangdong (CN); **Xianan Liu**, Guangdong (CN); **Xi Peng**, Guangdong (CN); **Jianping Li**, Guangdong (CN)

(73) **Assignee:** **GUANGDONG MIDEA CONSUMER ELECTRIC MANUFACTURING CO., LTD.**, Foshan (CN)

(**) **Term:** **15 Years**

(21) **Appl. No.:** **35/519,639**

(22) **Filed:** **Jan. 6, 2023**

(80) **Hague Agreement Data**

Int. Filing Date: **Jan. 6, 2023**

Int. Reg. No.: **DM/226363**

Int. Reg. Date: **Jan. 6, 2023**

Int. Reg. Pub. Date: **Jan. 12, 2024**

(30) **Foreign Application Priority Data**

Primary Examiner — Joseph Kukella

Assistant Examiner — Darryl J Dardenne

(57) **CLAIM**

The ornamental design for a beverage maker, as shown and described.

DESCRIPTION

2.1 : Perspective

2.2 : Front

2.3 : Back

2.4 : Left

2.5 : Right

2.6 : Top

2.7 : Bottom

3.1 : Perspective

3.2 : Front

3.3 : Back

3.4 : Left

3.5 : Right

3.6 : Top

3.7 : Bottom

FIG. 2.1 to FIG. 2.7, and FIG. 3.1 to FIG. 3.7 show a beverage maker according to different embodiments of the present design, respectively.

1 Claim, 14 Drawing Sheets
